TOY MACHINE GUN

Louis V. Aronson, Newark, N. J., assignor to Art Metal Works, Inc., a corporation of New Jersey

Application August 24, 1933, Serial No. 686,517

9 Claims. (Cl. 46—10)

My invention relates to toys, and more particularly, to toy guns such, for example, as toy machine guns.

In accordance with my invention, a toy machine gun is provided with mechanism for automatically affecting the passage, in rapid succession, of showers or puffs of sparks from the barrel of the gun.

Various other objects, advantages and features 10 of my invention will become apparent from the following detailed description.

My invention resides in the toy gun, combinations and arrangements of the character hereinafter described and claimed.

15 For an understanding of my invention and for an illustration of some of the many forms thereof, reference is to be had to the accompanying drawings, in which:

Figure 1 is a plan view of a toy machine gun assembly as constructed in accordance with my 20 invention;

Fig. 2 is a side elevational view, partly in section, of the machine gun assembly shown in Fig. 1;

Fig. 3 is a vertical sectional view, partly in 25 elevation, and is taken on the line 3—3 of Fig. 2;

Fig. 4 is a vertical sectional view, partly in elevation, of the assembly shown in Fig. 1;

Fig. 5 is a vertical sectional view, partly in 30 elevation, and is taken on the line 5—5 of Fig. 4 looking in the direction of the arrows;

Fig. 6 is a vertical sectional view, partly in elevation, and is taken on the line 6—6 of Fig. 4 looking in the direction of the arrows; and

Fig. 7 is a perspective view illustrating parts 35 of my novel mechanism.

Referring to the drawings, 1 represents any suitable base having a pair of plates 2 and 3 upstanding therefrom and secured thereto in 40 any suitable manner, said plates 2 and 3 being maintained in spaced relation by suitable transverse members. Journalled in the plates 2 and 3 is a transversely disposed shaft 4 actuable by a suitable winding key 5, Fig. 3. Secured to the 45 shaft 4 for rotatable movement therewith is a ratchet wheel 8 which, as shown in Fig. 3, is disposed at one side of and immediately adjacent the spiral spring arrangement 6. The ratchet disk 8 is a 50 resilient disk-like member having a pawl tooth 8a inherently biased in a direction from left to

right, Fig. 3, and is disposed flatwise against a pinion 9 loosely mounted on the shaft 4, said pinion 9 being provided with a plurality of radial slots 9a engageable one at a time by the pawl tooth 8a. The pinion 9 is maintained in operative position on the shaft 4 by a hub 10 rotatable with said shaft 4 and having a disk face 10a engaging one face of said pinion 9.

The pinion 9 meshes with and drives a pinion 11 rotatable with a shaft 12 journaled in the aforesaid plates 2 and 3. Rotatable with this shaft 12 is a cam disk 13 having a plurality of low surfaces 13a, the latter being utilizable as hereinafter described. The shaft 12 also carries a pinion 14 which is fixed thereto and which meshes with a pinion 15 rotatable with a shaft 16 journaled in the plates 2 and 3. The shaft 16 has rotatable therewith a second pinion 17 which meshes with and drives a pinion 18 mounted on a shaft 19 journaled in the plates 2 and 3. The shaft 19 has a second pinion 20 fixed thereto for rotatable movement therewith, said pinion 20 meshing with and driving a pinion 21 rotatable with a shaft 22 journaled in said plates 2 and 3. The shaft 22 has a wheel 23 rotatable therewith, the wheel 23 having its outer peripheral surface 23a formed from suitable abradant material such, for example, as is customarily used in the pyrophoric spark-producing art for coaction with the pyrophoric metal.

As clearly appears from a consideration of Figs. 4 and 5, the plate 2 carries a loosely pivoted lever 24 having a knob section 24a. The lever 24 also comprises a section 24b which extends laterally toward the wheel 23 and then interiorly 35 between the plates 2 and 3, said section 24b terminating in a detent section 24c coactable, for locking purposes, with the aforesaid pinion 21.

With the lever 24 in the position shown in Fig. 4, the lever detent section 24c coacts with the 40 pinion 21 and prevents operation of the hereinbefore described train of pinions. At this time, the key 5 may be operated to cause rotation of the shaft 4 in a counter-clockwise direction, Fig. 4, such movement of the shaft 4 serving to rotate 45 the ratchet disk 8 in a similar direction with respect to the stationary pinion 9, and to wind the spring 6. Upon completion of the winding operation, pressure on the key 5 may be relieved whereupon the shaft 4 moves slightly in 50 a clockwise direction, Fig. 4, until the ratchet disk 8 carried thereby comes into locking engagement at its pawl tooth section 8a with one of the slots 9a of the pinion 9.

After the spring 6 has been wound, the lever 55

24 may be moved in a counter-clockwise direction, Fig. 4, to remove its locking detent section 24c from engagement with the pinion 21. As a result, the described train of pinions are released for operation and, under the influence of the spring 6, rotatable movement is transmitted from each pinion to the succeeding one of the train in turn to thereby rotate the wheel 23 at a very rapid rate compared with the relatively slow rotative movement of the pinion 9 under the direct influence of the spring 6.

The plate 2 comprises an upwardly extending section 2a and, similarly, the plate 3 comprises an upwardly extending section 3a, Fig. 6, these sections 2a and 3a being provided with apertures transversely aligned for the reception of the lateral end sections 25a and 25b of a lever 25 which comprises a horizontal section 25c and a section 25d depending between the plates 2 and 3 and terminating in a nose section 25e coactable with the aforesaid cam disk 13. As clearly shown in Fig. 7, the end section 25b of the lever 25 comprises an extension 25f forming a fixed support for one end of a lever 26 which is connected to the lever 25 by a pin 27. The lever 26 terminates in a lateral section 28 which is disposed above the wheel 23, said lateral section 28 carrying an element 29 formed of pyrophoric material which, when engaged with the abradant surface 23a of the wheel 23, is adapted to produce a shower of sparks.

The horizontal section 25c of the lever 25 comprises an upstanding section 25g which, in suitable manner, supports a figure 30, Fig. 6, simulating the head of a helmeted soldier.

On opposite sides of the abradant wheel 23, the plates 2 and 3 define the respective upstanding sections 2b and 3b which form a support for a frame structure 31 secured thereto in any suitable manner, said frame structure 31 comprising a horizontal section 31a, a rearwardly inclined section 31b, a front vertical section 31c, and a front inclined section 31d. The front vertical section 31c of the frame structure forms a support for a horizontally disposed gun barrel 32 which preferably is provided with transverse apertures 32a. The section 3b of the plate 3 is provided with a slot thru which extends the aforesaid lateral section 28 of the lever 26, Fig. 2.

50 Resting upon and suitably secured to the horizontal section 31a of the frame structure 31 is a plate 33 having an inclined section 33a disposed in front of the helmeted figure 30, said inclined section having a peep hole 33b. The plate 33 may also comprise spaced, depending sections 33c forming a notch toward and into which the helmeted figure 30 is movable in the manner hereinafter described.

The aforesaid base 1 is adapted to carry a casing 34 which forms a housing for the herein described gear mechanism and which is adapted to be secured to the base 1 in any suitable manner, as by the lug members 1a. The casing 34 is provided with an aperture 34a through which projects the gun barrel 32 and associated supporting structure, the helmeted figure 30, and the lever 26.

As is clearly shown on the drawings, the casing 34 is shaped, as at 35, so as to constitute the representation of a reclining soldier whose left arm 35a extends forwardly and appears to hold what appears to be the housing of the machine gun as represented by the parts 3a, 3b, 31, etc. The helmeted figure 30 represents the head of this soldier while the color and con-

figuration of the lever 21 represents the soldier's right arm.

The casing 34 simulates an embankment and is suitably colored with this end in view. The figure of the reclining soldier is also suitably colored so as to impart a realistic appearance to the toy as an entirety. To an observer, therefore, it appears that the soldier is reclining on the slope of an embankment and that his hands are extended forwardly so as to hold the machine gun in operative position with the plate 33 serving as a shield against the bullets of the enemy, the machine gun housing as represented by the parts 3a, 3b, 31, etc. also having a characteristic color contributing to the effect presented by the device as a whole.

There hereinbefore described lever section 25d is so pivoted that it is biased, under the influence of gravity, so as to swing in a clockwise direction, Fig. 4. The nose section 25e of this lever 25d is coactable with the cam disk 13 and, when said nose section 25e is received within one of the low surfaces 13a of said cam disk 13, the lever 26 is in its lower position with the pyrophoric element 29 resting upon the wheel 23, and the upstanding section 25g of the lever 25 together with the helmeted section 30 carried thereby are in forwardly inclined positions. When the aforesaid nose section 25e is related to the cam disk 13 as shown in Figs. 4 and 7, the lever 26 is in an upward position with the pyrophoric element 29 removed from the wheel 23, and the lever section 25g together with the helmeted section 30 carried thereby occupy their upper positions.

Assuming that the spring 6 has been wound by insertion of the key 5 through the opening 34b provided therefor in the casing 34, the lever 24 may be moved counter-clockwise, Fig. 4, to remove its locking detent section 24c from engagement with the pinion 21. As a result, under the influence of the wound spring 6, operation of the train of pinions is effected whereby the wheel 23 rotates at a rapid rate and the cam disk 13 rotates at a substantially less rapid rate. During continuous rotation of the cam disk 13, the lever section 25d is oscillated whereby, through the chain of connections, the pyrophoric element 29 is moved rapidly into and out of engagement with the wheel 23. Each time that the pyrophoric element 29 engages the abradant surface 23a of the wheel 23, a shower of sparks are produced and, inasmuch as the gun barrel 32 is positioned substantially tangentially with respect to the periphery of the wheel 23 at the spot engaged by the pyrophoric element 29, it follows that these sparks are discharged through the gun barrel 32 and pass from the end thereof to thereby simulate the discharge of a gun, said sparks also being viewable through the openings 32a to thereby enhance the desired effect.

The aforesaid movement of the pyrophoric element 29 into engagement with the wheel 23 is effected directly in response to downward movement of the lever 26 under the control of the pin 27, and since this lever represents the right arm of the reclining soldier, it appears to an observer that downward movement of the soldier's right arm causes the discharge of the gun.

As clearly appears from the foregoing description, movement of the lever section 25g is timed with the movement of the lever 26. Therefore, the helmeted figure 30 or the representation of the soldier's head oscillates backward and for-

ward in synchronism with lever 26 or the representation of the soldier's right arm. To an observer, it appears, therefore, that the soldier is intermittently moving his head downwardly in order to observe his target through the peep hole 33b of the member 33a.

After the spring 6 has been unwound, the locking detent 24c of lever 24 may be returned to the position shown in Fig. 4 to thereby lock the train 10 of pinion mechanism. Thereupon, the key 5 may be actuated to wind the spring 6 and place the device in condition for subsequent operation.

While the invention has been described with respect to a certain particular preferred example 15 which gives satisfactory results, it will be understood by those skilled in the art after understanding the invention, that various changes and modifications may be made without departing from the spirit and scope of the invention and it 20 is intended therefore in the appended claims to cover all such changes and modifications.

What is claimed as new and desired to be secured by Letters Patent is:

1. The combination with a figure representative of a human being, of a continuously rotating wheel having an abradant surface, a pyrophoric element intermittently movable into engagement with said wheel to produce successive showers of sparks, a structure simulating a gun barrel traversed by said sparks as they pass from said wheel, and means whereby a part of said figure is moved substantially in synchronism with the production of said showers of sparks.

2. The combination with a figure representative of a human being, of a continuously rotating wheel having an abradant peripheral surface, a pyrophoric element intermittently movable into engagement with said wheel to produce successive showers of sparks, a structure simulating a gun barrel tangentially disposed with respect to said wheel, said gun barrel being traversed by sparks as they pass from said wheel, and means whereby a part of said figure is moved substantially in synchronism with the production of said showers of sparks.

3. In combination, mechanism for producing successive showers of pyrophoric sparks, a casing for said mechanism, a toy machine gun having a structure simulating a gun barrel projecting from said casing, said gun barrel being traversed by said sparks, and a figure associated with and forming a part of said casing, said figure being representative of a reclining soldier serving as the operator of said machine gun.

4. In combination, mechanism for producing successive showers of pyrophoric sparks, a casing for said mechanism, a toy machine gun having a structure simulating a gun barrel projecting from said casing, said gun barrel being traversed by said sparks, and a figure on said casing representative of a reclining soldier serving as the operator of said machine gun, said figure comprising a

lever representing an arm of said soldier, and means for oscillating said lever in synchronism with the production of said showers of sparks.

5. In combination, mechanism for producing successive showers of pyrophoric sparks, a casing 5 for said mechanism, a toy machine gun having a structure simulating a gun barrel projecting from said casing, said gun barrel being traversed by said sparks, a figure on said casing representative of a reclining soldier serving as the operator of 10 said machine gun, said figure comprising a pair of levers, one representing an arm of said soldier and the other forming a support for the soldier's head, and means for oscillating said levers in synchronism with the production of said showers of 15 sparks.

6. In combination, mechanism for producing sparks, a casing for said mechanism, said casing simulating an embankment, a toy machine gun having a structure simulating a gun barrel 20 projecting from said casing, said gun barrel being traversed by said sparks, and a figure associated with said casing, said figure being representative of a soldier serving as the operator of 25 said machine gun.

7. In combination, mechanism for producing sparks, a casing for said mechanism, said casing simulating an embankment, a toy machine gun having a structure simulating a gun barrel projecting from said casing, said gun barrel being 30 traversed by said sparks, a figure associated with said casing, said figure being representative of a soldier serving as the operator of said machine gun, and means whereby a part of said figure is moved substantially in synchronism with the 35 operation of said mechanism.

8. The combination with a figure representative of a human being, of a wheel having an abradant surface, a train of pinion mechanism 40 for rotating said wheel, a pyrophoric element, means operated by said pinion mechanism for intermittently moving said pyrophoric element into engagement with said wheel, said means comprising a cam operated by said pinion mechanism and a lever actuated thereby, said lever controlling movement of said pyrophoric element, and means whereby a part of said figure is moved 45 by said cam.

9. A toy machine gun provided with an elongated body structure adapted to be supported substantially horizontally, a structure simulating the muzzle of the gun, said gun muzzle structure projecting from said body structure, a motor in said body structure to the rear of and below said gun muzzle, an abrasive wheel driven by said motor, speed-increasing gearing between said motor and said abrasive wheel, and a pyrophoric element arranged to engage said abrasive wheel 55 in such relation that sparks are passed in substantially a horizontal direction at the muzzle of the gun.

LOUIS V. ARONSON.
